UNITED STATES PATENT OFFICE

ROBERT A. CURRIE, OF SYRACUSE, NEW YORK, ASSIGNOR TO R. E. DIETZ COMPANY,
OF NEW YORK, N. Y.

LAMP

Application filed March 12, 1929. Serial No. 346,429.

This invention relates to improvements in lamps or torches, and more particularly to improvements in torches of that type which are shaped and weighted so as to be self-righting, that is, which are adapted, when upset or moved out of the normal upright position, to automatically resume such position. Such torches are employed, for instance, along road excavations, at places where construction work is in progress, and for other out-of-door uses, as danger signals or warnings to traffic, and they are usually made of a sturdy construction and shape capable of withstanding severe usage and not being readily injured by falling or by being struck by vehicles or horses hoofs.

One object of my invention is to provide simple and practical means of novel construction for securing in the base of the torch, the weight which is employed for making the torch self-righting.

Another object of the invention is to provide a practical and simple device of novel construction which performs the several functions of a handle for carrying the torch; a lever for turning the burner or wick tube to secure it to and disconnect it from the torch body or font; and means for holding the wick in adjusted position in the burner or wick tube and preventing the wick from being accidentally shifted or pulled out of the tube, particularly when manipulating the latter to secure it to or detach it from the torch body.

Another object is to improve the construction of torches or lamps in the other respects hereinafter described and set forth in the claims.

In the accompanying drawings:

Fig. 1 is a view, partly in elevation and partly in section, of a torch lamp embodying my invention.

Fig. 2 is a sectional plan view thereof on line 2—2, Fig. 1, showing by full and broken lines two different positions of the handle or carrying bail.

Fig. 3 is a section thereof on line 3—3, Fig. 1, showing the bail in position to free or release the wick so that it can be adjusted in the burner or wick tube.

The body 10 of the torch is preferably of hollow, substantially spherical or globular form with a flattened base or bottom 11 on which the torch is adapted to rest in the normal or upright operative position, the globular form of the body permitting it, if upset or knocked over, to roll on its convexed side portions and be readily returned to the upright position. The body constitutes the font or container for the oil which feeds the usual wick. The body may be made of sheet metal and composed of top and bottom substantially semi-spherical sections secured together by a suitable joint 12 extending circumferentially of the body at its part of greatest diameter. The body may, however, be made of other suitable material, form and construction.

13 is a weight or heavy rigid block in the base portion of the torch body 10, this weight being sufficiently heavy and disposed so as to retain the torch stably in upright position on its bottom or seat 11 and to cause the torch, if upset or knocked out of such normal position, to automatically return thereto. Preferably the weight is in the form of an annular block which is shaped to fit the inside surface of the base portion of the torch body 10 and is provided with a central opening 14, and is stationarily secured in place in the base of the torch body by a securing or fastening device 15 located in the opening 14. The securing device preferably is annular or of substantially cup shape and fits in the central opening 14 of the weight, being secured to the bottom of the torch body as by spot welding, indicated at 16, and having an outwardly flared or flanged upper edge 17 which overhangs and engages the correspondingly bevelled upper edge of the central opening 14 of the weight, thereby securing the weight 13 in position.

These parts are preferably assembled as follows: The weight is placed in position in the base of the torch body and the cup-shaped fastener is then placed in the hole in the weight and welded to the bottom of the body. The upper edge portion of the cup is then flanged outwardly tightly against the bevelled edge of the hole in the weight, whereby the weight is pressed downwardly against the

bottom of the torch and is securely and rigidly clamped between the bottom and the flange 17 of the fastener 15.

5 The burner or wick tube 18 of the torch preferably consists of a heavy metal tube provided with a screw-threaded lower portion which is adapted to be screwed into a screw-threaded opening 19 in the top end of the torch body. The wick 20 passes through this 10 burner or wick tube 18.

21 represents a handle or bail preferably pivoted to the wick tube 18 and adapted to serve as a handle for carrying the torch. As shown, this bail is of substantially U-form 15 and its opposite legs are provided with in-bent ends or pivots 22 and 23 which enter and are adapted to turn in opposite holes in the wick tube 18, whereby the bail is adapted to swing from the upright position shown in 20 Fig. 1 to a laterally projecting position indicated by broken lines in Fig. 2.

One end 23 of the bail extends through the wall of the wick tube into the wick passage 5 of the tube and is adapted to engage or partially penetrate the wick, as indicated in Fig. 1, thereby gripping or holding the wick in position in the burner or wick tube and preventing the wick from slipping or being accidentally pulled out of the burner or wick tube.

20 The handle or bail 21 is preferably formed of wire having sufficient resiliency to normally retain the end 23 of the bail protruding through the pivot hole of the burner or wick tube into engagement with the wick, 35 but the end of the bail can be moved outwardly, out of engagement with the wick, to permit the adjustment, insertion or removal of the wick, by pulling outwardly the leg of the bail to which the end 23 is connected.

40 To facilitate the disengagement of the end 23 from the wick, the burner or wick tube is preferably provided with a cam portion 25, see Figs. 2 and 3, which is so disposed with reference to the bail that when the bail is

45 swung down to horizontal position, the adjacent leg of the bail will engage the cam 25, which will spring the leg of the bail outwardly so as to withdraw and hold the end 23 out of engagement with the wick, as indicated in Fig. 3.

50 With the end 23 of the bail held in this position by the cam 25, the wick can be readily inserted into and adjusted in or removed from the burner or wick tube. Then, when the bail is moved out of engagement with the cam 25, the end 23 of the bail will spring inwardly and press into the wick, as indicated in Fig. 1, and thereby retain the wick stationary in the adjusted position in the burner or wick tube.

55 60 By swinging the bail or handle 21 down to a laterally projecting position, it serves as a convenient handle or lever for turning the wick tube to screw it into or out of the threaded hole in the torch body. It will thus be noted that the bail or handle 23 serves the

three-fold purpose of a carrying handle for the torch; a lever or handle for turning the wick tube; and a securing device for holding the wick in adjusted position in the burner or wick tube.

70 I claim as my invention:

1. In a lamp, the combination of a body, a wick tube secured to said body by a turning movement of the wick tube, and a handle connected to said wick tube to move from an upright position in which it serves as a carrying handle for the lamp, to a laterally projecting position in which it serves as a lever for turning the wick tube to secure it to and disconnect it from the lamp body.

75 2. In a lamp, the combination of a body, a wick tube secured to said body by a turning movement of the wick tube, and a U-shaped bail having inturned ends pivoted in holes in said wick tube whereby the bail is adapted to swing from an upright carrying position to a laterally projecting position in which it serves as a lever for turning said wick tube.

80 3. In a lamp, the combination of a body, a wick tube thereon, a wick passing through said tube, and a carrying handle for said lamp having a part projecting through said wick tube into engagement with said wick for holding the wick in place in the wick tube.

85 4. In a lamp, the combination of a body, a wick tube thereon, a wick passing through said tube, a movable wick holder having a part projecting through said wick tube into engagement with said wick for holding the wick in place in the wick tube, and a part on said lamp adapted when said wick holder is moved into engagement therewith to withdraw said wick holding part from engagement with the wick.

90 5. In a lamp, the combination of a body, a wick tube thereon, a wick passing through said tube, and a carrying handle for said lamp having a pivot passing through a hole in said wick tube into holding engagement with said wick, and pivotally connecting said handle to said lamp, and a part on said lamp adapted when said handle is swung on its pivot to engage the handle and shift said pivot part out of engagement with the wick to release the wick.

95 6. In a lamp, the combination of a body, a wick tube thereon, a wick passing through said tube, and a bail having inwardly extending ends pivoted in holes in said wick tube, one of said ends being adapted to extend through the wall of the wick tube into engagement with the wick for holding the wick in place in the wick tube.

100 7. In a lamp, the combination of a body, a wick tube thereon, a wick passing through said tube, a bail having inwardly extending ends pivoted in holes in said wick tube, one of said ends being adapted to extend through

the wall of the wick tube into engagement with the wick for holding the wick in place in the wick tube, and a part on said wick tube adapted when said bail is swung on its pivot to engage the bail and shift said wick-holding pivot out of engagement with the wick to permit movement of the wick in the wick tube.

ROBERT A. CURRIE.
